UNITED STATES PATENT OFFICE.

GIOVANNI NOTO, OF TORRE DEL GRECO, ITALY, ASSIGNOR TO SERPE BROTHERS, OF NEW YORK, N. Y., A FIRM COMPOSED OF MARCO SERPE, VINCENT SERPE, ANTHONY SERPE, AND RAYMOND SERPE.

DESIGN FOR A CAMEO.

Application filed February 10, 1928. Serial No. 25,351. Term of patent 7 years.

To all whom it may concern:

Be it known that I, GIOVANNI Noto, a subject of the King of Italy, residing at Torre del Greco, in the district of Naples, Italy, have invented a new, original, and ornamental Design for Cameos, of which the following is a specification, reference being had to the accompanying drawing, forming part hereof.

I claim:

The ornamental design for a cameo, as shown and described.

GIOVANNI NOTO.
